CLAIM

The ornamental design for a network gateway as shown and described.

DESCRIPTION

FIG. 1 is a perspective view of a network gateway showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing the network gateway in use.

The broken lines shown in the figures are for the purpose of illustrating portions of the network gateway and form no part of the claimed design.
